UNITED STATES PATENT OFFICE.

LOUIS H. BACHE, OF TORRANCE, CALIFORNIA.

CEMENTING BACK-PRESSURE VALVE MEANS.

Application filed June 25, 1923. Serial No. 647,570.

To all whom it may concern:

Be it known that I, LOUIS H. BACHE, a citizen of the United States, residing at Torrance, in the county of Los Angeles and State of California, have invented a new and useful Cementing Back-Pressure Valve Means, of which the following is an invention.

This invention relates to valve means of the type employed to prevent cement from reentering a well casing when such casing is lowered into position after the quantity of cement necessary to cement the well has been forced through the casing.

An object of the invention is to insure that the cement will be maintained on the outside of the casing until the cement has set.

Heretofore, in cementing a well, cement would oftentimes flow back into the casing due to the fact that the pressure, which the operator sought to maintain within the casing, lowered for some reason or other below that of the column of cement around the casing. In using this invention it is unnecessary to maintain pressure within the casing after the cement has once been pumped into place.

The accompanying drawings illustrate one embodiment of the invention:

Figure 1 is a vertical mid section of cementing back pressure valve means constructed in accordance with the provisions of this invention, a fragment of casing being indicated in broken lines.

Fig. 2 is a plan section on the line indicated by 2-2, Figure 1.

Fig. 3 is an inverted plan section on the line indicated by 3-3, Figure 1.

In the drawings, a tubular member is indicated at 4 and may be, for example, the commonly employed casing shoe that is provided with internal screw threads 5 for screwing onto the lower end of the well casing, a fragment of which is indicated in broken lines *a*, Fig. 1. Mounted within the member 4 is a valve seat 6 which, in this instance, is threaded at 7 into the lower end of the tubular member 4. It will be evident that any other satisfactory means may be employed for connecting the valve seat to the casing. The valve seat 6 may be secured against unscrewing by any suitable means and, in the instance shown, a hollow nut 8 is threaded into the lower end of the tubular member 4 approximately into contact with

the valve seat 6. The nut 8 is open at its lower end, as indicated at 9, thus establishing a passage through the nut, valve seat and tubular member 4 for the passage of cement in the operation of cementing the well.

Adapted to close upon the valve seat 6 is a valve 10 having a stem 11 which slides within a stem guide 12 that, in this instance, is formed integral with the valve seat 6. The valve stem 11 is provided near its upper end with a shoulder 13, and surrounding the valve stem between said shoulder and the stem guide 12 is a coil spring 14 tending to move the valve 10 into engagement with the valve seat.

To releasably hold of the valve 10 against being closed by the expansive force of the spring 14, there are provided suitable releasable means which, in this instance, are released by downward pressure of the fluid upon slight elevation of the well casing to which the valve is connected. In this instance a suitable latch 15 is employed for releasably holding the valve 10 in open position. The latch is movably mounted in any suitable manner, being, in this instance, hinged or pivoted at 16 to the lower face of the valve seat at a sufficient distance from the axis of the valve stem so that the latch, when retracted, will not interfere with the closing movement of the valve 10.

When the latch 15 is aslant inwardly and downwardly as in Figure 1, the lower end thereof engages in an annular recess 17 in the valve 10 close to the periphery thereof, and further opening movement between the valve and valve seat will release the valve from the latch. When the latch is disengaged from the valve, gravity may be relied upon to retract it, but preferably a coil spring 18 is mounted on the pivot 16 with its opposite ends engaging the latch and the valve seat.

The invention operates as follows:

The well casing, to which the invention is attached, being in the well and the cement having been forced through the casing in a manner well understood in the art relating to the cementing of wells, the cement flows into the space surrounding the casing. When the cement is pumped past the valve 10 the pressure of the cement forces the valve wide open thus releasing it from the latch 15 which thereupon is swung outwardly out of the path of movement of the

valve. The pumping of the cement having ceased, the back pressure will predominate thus causing the valve to close upon its seat and prevent the cement from running back 5 into the casing which running, if it occurred, would lower the height of cement outside of the casing and permit such cement to set within the casing.

It will be clear from the foregoing that 10 the valve is released from the holding-means or latch 15 by reason of there being greater fluid pressure above the valve than the combined pressures exerted by the spring 14 and the fluid beneath the valve, 15 that I have provided valve means at the lower end of the casing to admit of the passage of cement from the casing to the space therearound and that the valve means may be actuated by raising of the casing to prevent 20 back flow of the cement into the casing.

In order to facilitate retracting of the valve 10, when it is desired to latch it in open position, the valve is provided on its lower face with an apertured lug 19. To 25 retract the valve, a hook or other suitable device will be inserted through the opening 9 and engaged with the lug 19 and the hook will be pulled to move the valve far enough from the seat 6 to permit the latch 30 15 to be swung into the position shown in Fig. 1.

I claim:

1. Cementing back-pressure valve means, comprising a valve seat, a valve to close 35 upon said seat, a spring tending to close the valve, and means to releasably hold the valve against closing, the valve being re-

leased from the holding means by pressure of the cement as it passes the valve.

2. Cementing back-pressure valve means, 40 comprising a valve seat, a valve to close upon said seat, a spring tending to close the valve, and means to releasably hold the valve in an open position, said valve being released from the holding means by further opening movement between the valve and valve seat.

3. Cementing back-pressure valve means, 45 comprising a valve seat, a valve to close upon said seat, a spring tending to close the valve, and means to releasably hold the valve in open position, said valve being released from the holding-means by greater fluid pressure above the valve than the combined pressure exerted by the spring and 55 the fluid beneath the valve.

4. The combination with a well casing, of valve means at the lower end thereof to admit of the passage of cement from the casing to the space therearound, said valve means being actuated by raising of the casing to prevent back flow of the cement into the casing.

5. Means for cementing a well comprising 60 a casing, and means associated with the casing and operating to admit of the passage of cement from the casing to the space therearound, said means being actuated by pressure of the cement to prevent back flow 65 of the cement in the casing.

Signed at Torrance, Calif., this 14th day 70 of June, 1923.

LOUIS H. BACHE.
